US0D1034071S

(12) **United States Design Patent** (10) Patent No.: **US D1,034,071 S**
(45) Date of Patent: ** Jul. 9, 2024

(54) **BLADE FOR A MICRO PUREE MACHINE**(71) Applicant: **SharkNinja Operating LLC**, Needham, MA (US)(72) Inventors: **Lukas Tubby**, London (GB); **Sam Bannister**, London (GB); **Helen Williams**, Needham, MA (US)(73) Assignee: **SHARKNINJA OPERATING LLC**, Needham, MA (US)(**) Term: **15 Years**(21) Appl. No.: **29/895,615**(22) Filed: **Jun. 23, 2023****Related U.S. Application Data**

(63) Continuation of application No. 29/845,156, filed on Jul. 5, 2022.

Primary Examiner — Ricky Pham(74) *Attorney, Agent, or Firm* — Burns & Levinson, LLP; Joseph M. Maraia(57) **CLAIM**

The ornamental design for a blade for a micro puree machine, as shown and described.

DESCRIPTION

FIG. 1 is a top, front and right side perspective view of the blade for a micro puree machine, embodying our new design;

FIG. 2 is a front elevation view thereof;

FIG. 3 is a rear elevation view thereof;

FIG. 4 is a left side elevation view thereof;

FIG. 5 is a top plan view thereof;

FIG. 6 is a right side elevation view thereof; and,

FIG. 7 is a bottom plan view thereof.

The broken lines in the drawings depict portions of the blade that form no part of the claimed design.
